UNITED STATES PATENT OFFICE.

FRANK E. LOWRY, OF ERIE, PENNSYLVANIA, ASSIGNOR OF ONE-HALF TO FRANK H. PAYNE,
OF ERIE, PENNSYLVANIA.

BARREL.

No. 869,209.

Specification of Letters Patent.

Patented Oct. 22, 1907.

Application filed February 6, 1907. Serial No. 356,003.

To all whom it may concern:

Be it known that I, FRANK E. LOWRY, a citizen of the United States, residing at Erie, in the county of Erie and State of Pennsylvania, have invented new 5 and useful Improvements in Barrels, of which the following is a specification.

This invention relates to barrels and consists in certain improvements in the construction thereof as will be hereinafter fully described and pointed out in the 10 claims.

The object of the invention is to provide barrels preferably the ordinary stave barrel, in which is arranged the usual croze with a head of concavo-convex form with the convex side within the barrel, the edges 15 of the head resting in the croze and the head made elastic circumferentially by corrugations extending from the extreme edge inwardly, so that when the head is subjected to the pressure of the material within the barrel, the thrust incident to the arch shape is 20 delivered almost entirely to the body of the barrel as distinguished from being absorbed by the material forming the head as would be the case with a structure of concavo-convex form, but without the corrugations. As a result of this construction, the edge of the head 25 more firmly engages the body of the barrel at the croze so as to prevent its displacement in ordinary usage. The corrugations materially stiffen the head, that is, prevent local distortion with a resulting displacement.

The invention is illustrated in the accompanying 30 drawings as follows:

Figure 1 shows a plan view of the head. Fig. 2, a side elevation of the barrel. Fig. 3, a section of a barrel, the head arranged therein being partly in section.

1 marks the barrel body. Ordinarily this would be 35 formed of wooden staves. 2 the hoops which are arranged in the usual manner; 3 the croze; 4 the upper surface of the croze which in the preferred construction coincides with the edge of the head as hereinafter described.

40 5 marks the head. It is of concavo-convex form with the convex side within the barrel. This is provided with the corrugations 6 which extend radially preferably from the center to the edge 7. These corrugations make the edge 7 comparatively elastic or extensible circumferentially so that when weight is put 45 on the head, the thrust incident to the arch shape of the head is delivered almost entirely to the body of the barrel along the croze.

I prefer to have the surface 4 coincident with the edge of the head that is to say the surface 4 is so formed 50 with relation to the convolutions of the edge of the head as to contact all points along the edge as distinguished from a surface or shape of croze that will contact the apexes or bends only of the convolutions, so that the corrugated edge will form a fit throughout the 55 length of the edge. The thrust incident to the pressure on the arch shaped head will form more or less of an indenture in the comparatively soft material in which the croze is formed so that any slight unevenness there may be in the surface does not prevent the 60 forming of a tight joint. The thrust, therefore, incident to the elastic edge and arch shaped head not only more firmly engages the edge of the croze so as to prevent displacement, but also insures a more perfect closure. This is particularly desirable where the 65 barrel is to be used for liquids or fine materials.

What I claim as new is:

1. In a barrel the combination with the body portion of the barrel having a croze formed therein; of a barrel head of concavo-convex shape with the convex side within the 70 barrel and having corrugations extending from the extreme edge of the head inwardly, the edge of the head resting in the croze.

2. In a barrel the combination with a body portion of the barrel having a croze formed therein; of a barrel head of concavo-convex shape with the convex side within the barrel and having corrugations extending from the extreme edge of the head inwardly, the edge of the head resting in the croze, the surface of the croze engaged by the head being coincident with the edge of the head. 75

3. In a barrel the combination with the body portion of the barrel formed of comparatively soft material and having a croze formed therein; of a barrel head formed of comparatively hard material and of concavo-convex shape with the convex side within the barrel and having corrugations extending from the extreme edge of the head inwardly, the edge of the head resting in the croze and with the surface of the croze engaged by the head coincident with the edge of the head. 85

4. In a barrel the combination with the body portion of the barrel having a croze formed therein; of a head of concavo-convex shape with the convex side within the barrel and having corrugations extending from the extreme edge of the head inwardly, the edge of the head resting in the croze, the head having a greater normal diameter than 90 the body of the barrel at the outside edge of the croze. 95

In testimony whereof I have hereunto set my hand in the presence of two subscribing witnesses.
